UNITED STATES PATENT OFFICE.

NAPOLEON DU BRUL, OF CINCINNATI, OHIO.

DESIGN FOR A CIGARETTE-MACHINE FRAME.

SPECIFICATION forming part of Design No. 32,639, dated May 8, 1900.

Application filed March 28, 1900. Serial No. 10,553. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for a Cigarette-Machine Frame, of which the following is a specification.

My new design is illustrated in the accompanying drawing, which is an isometric perspective view of a cigarette-machine frame embodying the same.

The leading or material features of my design are the elongated approximately-rectangular structure tapering upwardly from the base, rounding at one end and having a vertical offset in the upper portion, open sides formed by vertical members, and intersecting

longitudinal and transverse horizontal members, said vertical and horizontal members having inwardly-presented flanges. In addition to these material features it will be seen that the uppermost flanges are continued inwardly and meet to form an upper surface. Said upper surface is slotted, as shown.

Having thus described my invention, what I claim as new, and desire to secure by Letters Patent, is—

The design for a cigarette-machine frame, substantially as herein shown and described.

Signed at New York, N. Y., this 17th day of January, 1900.

NAPOLEON DU BRUL.
